UNITED STATES PATENT OFFICE.

THOMAS RIGBY AND GEORGE W. ANDREW, OF DUMFRIES, SCOTLAND, ASSIGNEES TO
WETCARBONIZING LIMITED, OF LONDON, ENGLAND.

PEAT-DEWATERING PROCESS.

1,121,203.

Specification of Letters Patent.

Patented Dec. 15, 1914.

No Drawing.

Application filed March 6, 1914. Serial No. 822,972.

To all whom it may concern:

Be it known that we, THOMAS RIGBY and GEORGE WILLIAM ANDREW, subjects of the King of Great Britain and Ireland, and residents of 61 Loreburn street, Dumfries, Scotland, have invented a certain new and useful Improved Peat-Dewatering Process, of which the following is a specification.

This invention relates to the dewatering of peat by a process of the known kind in which a physical or chemical change is induced in the wet material and the water as a consequence rendered more easily expressible.

15 Ekenberg (see *Journal of the Iron and Steel Institute* 1909, page 313) showed that if peat was heated while wet to a fairly elevated temperature a change of the kind referred to occurred and, apparently as the 20 result of decomposition of a slimy water-binding hydrocellulose, that the bulk of the water then became readily expressible. This process has long been accepted as the ideal one for dewatering peat because of the 25 positive manner of its action and as applicable therefore with certainty to all the very different kinds of peats, but despite its advantages much study and expense has been involved in the reduction to the lowest possible 30 limits of the heat necessary to bring about the change to the full extent desired. Now we have ascertained that an alternative and in some respects more conveniently available method of securing economy is to 35 utilize the accelerating power on the reaction which we have found acids to possess. Thus our experiments show that not only can a greater degree of expressibility be secured for any given time of heating at any 40 particular temperature, if the peat is acidified but that conversely the same extent of change can be secured under conditions of lower temperature or shorter time of treatment or both with acidified peat than with 45 raw material.

During simple heating of the peat by the Ekenberg method acid matters are always generated in the peat water and apparently, according to our investigations, the 50 change leading to unbinding of the water does not occur even in the Ekenberg process until a sufficiency of free acid formed by decomposition consequent on heating is present in the peat. A particular advantage

of accelerating the reaction by the use of 55 added acid resides however in the fact that the desired change can then be secured with a lesser loss of nitrogen and solids of calorific value in the effluents the amounts of which bodies dissolved in the peat water 60 when the change is effected by simple heating often becoming serious. According to this invention therefore the Ekenberg treatment is carried out after the acidification of the raw peat. The acid, for instance, hydrochloric sulfuric or sulfurous acid, may be added before the commencement of the heat treatment or at some stage during the 65 same. In some cases the acid or acids used may be derived from the effluent separated 70 from a previously treated batch of material having been either originally added to that or an earlier previous batch or having been actually formed therein.

The treatment may most conveniently be 75 carried out according to either of the ways indicated in application No. 712745 differing chiefly only in the temperature and time of treatment of the material in the hottest portion of the wet-carbonizing apparatus the 80 material being afterward dewatered by pressing preferably still at a fairly elevated temperature say above 60° C. in the usual way.

As an instance of the effect produced by 85 some acids we may state that in certain of our experiments on a particular peat which when using simple heating needed to be maintained at 180° C. for some twenty minutes to secure a certain ease of removal 90 of the water, this peat after it had had an amount of acid (hydrochloric, sulfuric or sulfurous acid) added to it sufficient to render the acidity of the pulp $\frac{1}{10}$ to $\frac{1}{20}$ that of a normal solution of the acid was capable 95 of being just as easily dewatered after heating it for a few minutes to a temperature even below 100° C. In fact in some experiments with sulfurous acid satisfactory results were obtained even after only heating 100 the material for five minutes to a temperature of 60° C.

Having now described our invention, what we claim as new and desire to secure by Letters Patent is:—

1. A process for dewatering peat consisting in acidifying the wet peat, heating same while wet and without evaporation only un-

til the material loses its water-binding properties and then expressing the liberated water, as set forth.

2. A process for dewatering peat consisting in acidifying the wet peat, heating the same while wet to a temperature above the boiling point under a pressure sufficient to prevent ebullition and for a time sufficient only to render the bound water of the peat freely expressible cooling said peat to a temperature below the normal boiling point and expressing the liberated water from said peat; as set forth.

3. A process for dewatering peat consisting in adding acid to the wet peat in a quantity sufficient to give it an acidity about that of one-tenth to one twentieth normal solution of the acid, heating the acidified pulp without evaporation for a time suffi-

cient only to liberate the bound water and pressing the liberated water out of said peat; as set forth.

4. A process for dewatering peat consisting in heating peat while wet and without evaporation for a time sufficient to unbind the water of the mass, removing the liberated water from the peat mass, and adding acid matters contained in said liberated water to a further quantity of peat about to undergo treatment; as set forth.

In testimony whereof we have signed our names to this specification in the presence of two subscribing witnesses.

T. RIGBY.

G. W. ANDREW.
